United States Patent Office.

FREDERICK SHICKLE, OF ST. LOUIS, MISSOURI, ASSIGNOR TO
SHICKLE, HARRISON & CO.

Letters Patent No. 95,388, dated September 28, 1869.

IMPROVEMENT IN MOULDING PIPE.

The Schedule referred to in these Letters Patent and making part of the same.

To all whom it may concern:

Be it known that I, FREDERICK SHICKLE, of St. Louis, in the county of St. Louis, and State of Missouri, have made certain new and useful Improvements in Devices for Moulding Pipe, and for similar purposes; and I do hereby declare the following to be a full and correct description thereof, reference being had to the accompanying drawings, and to the letters of reference marked thereon.

The object of this invention is to form a true and proper mould for casting pipes, columns, or similar bodies, especially such as are of great size and weight; and

The nature of said invention is in arranging the mould-frame or flask upon movable tables, by which said frame or flask may be adjusted about the pattern, this being, at the same time, supported in proper vertical position upon a spindle, secured to a stationary bed-plate.

To enable those herein skilled to make and use my said improvements, in their usual application in pipe-moulding, I will now more fully describe the same, referring to—

Figure 1 as a longitudinal sectional elevation; to

Figure 2 as a plan of the tables and bed-plate, as seen after the flasks and cores are lifted off.

I form the flask in halves, L and L', supporting each half flask upon a table, M or M'. To insure a proper vertical position of the flask, said parts are held by pins m and m', respectively, or by clamps.

The tables M and M' move longitudinally on the ways or slides N, and to regulate and effectuate said movement, a screw-shaft may be used, to move a proper nut, connected with each of said tables, or a rack and pinion, or similar devices may be employed.

Between the slides N, and strongly connected therewith, to form a united frame, is arranged the centre plate O, having the vertical central spindle P.

Resting upon the bed-plate O, and guided by the spindle P, is the pattern-frame Q. Said frame Q is a stout rectangular frame, for supporting the pattern Q'. The arrangement of these parts is such, that by any usual derrick or hoisting-device, the frame Q and its

pattern, as well as the flask-halves L and L', may be lifted off, or into position and adjustment.

The pattern Q will be constructed to move in or out from its central axis, so that after the mould has been formed, said pattern may be drawn back from contact with the sand in the flask L and L', and thus leave well-defined edges, so that when the flask-halves are afterward joined, the joint will be comparatively imperceptible.

This movement of the pattern will be effected by cam, or other devices, within the same, acting (under power of the operator) to move out the semicylinders of the pattern Q from the frame Q, or recede the same into said frame.

To make a proper joint at the base, the flask L L' has an annular rim, l l', with which the pattern Q' connects nicely, when the parts are in close adjustment.

In the use of my said improvements, after the sand has been properly rammed in between the flask and pattern, the pattern Q' being receded, the sand in the flask forms the mould-surfaces, the dividing edge at the vertical frame Q being nicely preserved, (by the operation of withdrawing the pattern into the frame.) The flask-halves are then disconnected from each other, by releasing the usual clamps, or other holding-devices, whereupon the tables M and M' are moved away from the central frame Q, by the devices as before indicated, and the frame Q, and its pattern is then lifted off its spindle and support; the flask-halves are then again moved to a joint, and secured together, whereupon they may also be lifted off the tables M M', to be dried, and used in the usual manner.

Having thus fully described my said invention,

What I claim, is—

1. The flask L L', supported vertically upon sliding tables M M', substantially as set forth.
2. Supporting the pattern-frame Q by the centre-plate O and spindle P, substantially as set forth.

In witness of said invention, I have hereunto set my hand in the presence of—

Witnesses: FREDERICK SHICKLE.
